CHARLES E. LUCKE, OF NEW YORK, N. Y., ASSIGNOR, BY MESNE ASSIGNMENTS, TO
FULLER LEHIGH COMPANY, A CORPORATION OF DELAWARE

GAS PRODUCER AND STEAM BOILER

Application filed April 13, 1928. Serial No. 269,659.

This invention relates to a steam boiler below the setting of which a rotating gas producer is located and the producer gas passes directly into the boiler furnace where air is 5 intimately mixed therewith for combustion purposes.

The invention will be understood from the description in connection with the accompanying drawings, in which Fig. 1 is a vertical section through an illustrative embodiment of the invention; Fig. 2 is a section along the line 2—2 of Fig. 1; Fig. 3 is a section on an enlarged scale showing one of the details; Fig. 4 is a vertical section, partly 15 broken away, showing a modification; Fig. 5 is a horizontal section through the furnace of another modification, and Fig. 6 is a section along the line 6—6 of Fig. 1.

In the drawings, reference character 1 indicates the furnace of a boiler above which 20 a water tube boiler may be located. Only a portion of the boiler is shown with the inclined tubes 2 that are connected to uptake and downtime headers in the well-known 25 way. The furnace walls are indicated at 3 and the furnace is open at the lower end.

Horizontal headers 4 and 5 are located outside of the furnace walls and are connected to the water circulation system of the boiler 30 by pipes 6 and 7, respectively. The headers 4 and 5 are connected by rows of tubes 8 extending through the furnace, the rows being separated some distance from each other. Air ducts 9, preferably made of refractory 35 material and being provided with openings 10 on opposite sides thereof, extend from the air space 11 outside of the boiler furnace and rest upon the tubes 8. The air space 11 is supplied with air under pressure through the 40 inlet 12 from any convenient source so that the air will be forced out through the openings 10.

A rotary gas producer 15 is located below the furnace and is circular in cross-section. 45 The upper edge of the wall of the producer is provided with a circular groove 16 into which a flange 17 at the lower end of the furnace projects to form a gas-tight seal.

The gas producer is rotated by means of 50 a pinion 18 driven from any convenient source

of power. The pinion 18 meshes with a circular rack 19 on the gas producer and the producer is supported on supporting rollers 20 that roll upon a circular track 21. An ash hopper 22 is provided in the lower portion of 55 the producer and a stationary plow 23 extends into the same to remove the ash that accumulates.

A blast inlet 24 extends into a pipe 25 in the lower end of the producer to supply air and 60 steam in proper proportions. Hoods 26 are located above the pipe 25 and serve to distribute the blast passing out of the upper end of the pipe 25. Branches 27 extend from the pipe 25 into an annular distributor 28 in the 65 wall of the producer and holes or openings 29 are provided on the inside of the distributor 28 to permit air to pass into the producer.

A coal feed or spout 30 provided with a regulating valve 31 extends through the lower 70 portion of the furnace wall 3 and feeds coal into the producer below the furnace. A hollow stirrer or coal bed agitator 32 also extends through the lower portion of the furnace wall 3 and is revolvable in a bearing 33 75 in this wall. The projecting end of the agitator extends downwardly into the coal bed and an oscillating rod 34, operated by an eccentric 34' or in any other convenient manner, is connected to an arm 35 on the stirrer 32 and serves to oscillate the same in its bearing 33, so that the stirrer or coal bed agitator 80 can be turned to stir the mass over the entire upper area of the producer coal bed. A water pipe 36 extends into the stirrer 32 85 through a bushing 37 and cooling water passes into and through this pipe 36 from the hose 38 and passes into the annular space between the pipe and stirrer 32, thence out through 90 the outlet 39.

In the modification shown in Fig. 4, the parts similar to those already described are designated by the same reference characters and it is not thought necessary to repeat the description of those parts. In this modification, a pipe 40 extends across the lower portion of the furnace and is movable in bearings in the furnace walls, so that the stirrer 95 or coal bed agitator 41 can be moved to stir all parts of the upper portion of the coal bed 100.

in the producer 15. The pipe 42 is provided for introducing water for cooling the stirrer and the pipe 40. The coal inlet 43 is provided with a screw conveyor 44 to feed coal into the producer 15.

- 5 In the modification shown in Figs. 5 and 6, the lower portion of the furnace wall 45 is provided with a ledge or inward extension 46 and the coal feeder 47 enters the furnace 10 slightly above the ledge 46 so that, when the coal is introduced through the feeder 47, it will remain for a sufficient length of time upon the ledge 46 to become heated sufficiently to be sticky when it falls into the 15 producer 15. This is especially useful to prevent dust from rising from the coal and causing slag to form from the ashes as the hot products of combustion pass through the furnace.
- 20 By this invention, producer gas is produced in a producer without the usual top and enters the lower end of the boiler furnace without the usual bottom where combustion air is intimately mixed with the same at a 25 plurality of points as the combustion air passes from the air ducts 9 through the openings 10. In this way a hot zone is produced above the air admission ducts and there is a cooler zone below these ducts. The ducts 30 limit the radiant heat that would otherwise pass from the hot furnace walls above the ducts down on top of the producer bed and its parts, thus leaving the top of the producer at about the same temperature as in ordinary 35 producers. The same means result in a high degree of cleanliness as to slag forming solids in the upper hot zone.

Changes and modifications can be made without departing from the spirit and scope 40 of the invention.

I claim:

1. In a boiler, a furnace, a water tube boiler having tubes above said furnace, rows of parallel air ducts of refractory material extending across said furnace, the ducts in one row being staggered with respect to those in another row, said ducts being provided with openings whereby combustion air is supplied to the individual streams of rising fuel gases 45 into which said ducts divide the rising fuel stream, and water tubes extending across said furnace and supporting said ducts, said tubes being connected to the water circulation system of said boiler and absorbing heat from 50 said ducts.

2. In a boiler, a furnace, a water tube boiler having tubes above said furnace, rows of parallel air ducts of refractory material extending across said furnace, the ducts in one row being staggered with respect to those in another row, said ducts being provided with openings whereby combustion air is supplied to the individual streams of rising fuel gases 55 into which said ducts divide the rising fuel

stream, water tubes extending across said furnace and supporting said ducts, said tubes being connected to the water circulation system of said boiler and absorbing heat from said ducts, a rotary gas producer below said furnace, said producer having an open top located below the lower open end of the boiler furnace and constituting its closure, and a coal feeder and a stirrer for said producer supported by the walls of said furnace. 70

CHARLES E. LUCKE. 75
